INVENTOR
Charles W. Hack
BY Arthur C. Brown
ATTORNEY

UNITED STATES PATENT OFFICE.

CHARLES W. HACK, OF TOPEKA, KANSAS.

COOLING-MEDIUM CONTAINER.

Application filed July 5, 1924. Serial No. 724,213.

This invention relates to refrigeration and the primary object thereof is to provide a cooling box for refrigerators in which there is a cooling medium, preferably brine and in 5 which is submerged or partially submerged a passageway, spaced above the bottom of the box a sufficient distance to maintain a cooling medium in the upper portion of the box at a temperature lower than that in the 10 bottom of the box to cause a circulation of the cooling medium in the box due to the difference in temperatures at the top and bottom of the box. Cooling boxes are sometimes designated brine tanks but in this application I shall refer to the same as a cooling box because mediums other than brine may be used and while the element in the brine tank for passing active refrigerant through the brine is usually termed the expansion coil, I shall refer to the expansion element as the passageway because it may or may not take the form of a coil. Indeed the construction of the means for 15 confining the refrigerant as it passes through the cooling box is not herein illustrated as of coil form, but obviously a coil may be employed for carrying out the generic embodiment of my invention.

Broadly the invention contemplates means 20 for maintaining the upper portion of the cooling box at a temperature below that in the bottom of the box so as to maintain a circulation of the cooling medium in the box and thereby facilitate the refrigerating action of the refrigerant and specifically the invention contemplates means whereby the compressor may not pull liquid refrigerant from the passageway, the refrigerant being maintained in the passageway until it is 25 vaporized. Therefore the refrigerant must complete its work before it may pass on to the compressor. I also am enabled to construct the cooling box so that certain partitions used for providing circulating passageways or ducts for the cooling medium may be utilized for compartments capable of receiving food and the like and capable of serving as freezing compartments for transforming water into ice for freezing puddings, sherbets, ices and the like. The various novel features of this invention as well as the advantages will be apparent by reference to the following description in connection with the accompanying drawings, in 30 which—

Fig. 1 is a vertical, longitudinal, sectional view through a cooling box constructed in accordance with my invention, and

Fig. 2 is a horizontal, sectional view through the box wall, the passageway for 60 the active refrigerant being shown in plane with parts being broken away to illustrate the conducting ribs.

Referring now to the drawings by numerals of reference—

1 designates the cooling medium container or outside casing of the box provided in its lower portion with two cooling compartments or receptacles 2 and 3 extending from the front to the rear. The rear portions of the receptacles 2 and 3 are spaced from the rear wall of the container 1 as are also the sides of the receptacles 2 to form spaces 4, 5, and 6, the front ends of the receptacles 2 and 3 being accessible through 65 openings normally closed by doors 7 and 8, hinged to the container at 9 and 10. The receptacles 2 and 3 are in parallel and spaced apart to provide an elongated circulating space 11, the bottoms of the receptacles also being spaced from the bottom of the receptacle 1 to provide a lower passageway 12. The receptacles 2 and 3 are 70 may contain shelves or pans to receive food, ices and the like and one or more of the 75 pans may be provided with compartments to form blocks of ice as will be well understood. The top walls of the receptacles 2 and 3 are in a plane, a considerable distance below the top of the receptacle or casing 1 80 to provide a space for the passageway or conduit 13. The conduit 13 is shown as comprising a substantially rectangular hollow body with an opening 14 therein and it has an inlet 15 and an outlet 16, the inlets 85 and outlets being preferably diametrically opposite one another and the inlets and outlets consist of tubular members 17 and 18 having collars 19 and 20 to abut against the top of the container 1 preferably with 90 washers or gaskets surrounding the openings through which the protruding ends 21 and 22 of the threaded neck-like portions project. The threaded neck-like portions receive jam nuts 23 and 24 to secure tubular 95 members to the top of the box and the necks are internally threaded to receive the inlet pipe 25 and the outlet pipe 26 as will be clearly seen by reference to Fig. 1. The conduit 13 is substantially ring-shaped and 100 it is provided with radial surrounding 105 conducting flanges or ribs 27 in line with in-

ternal radial conducting flanges 28 which extend entirely around the inner walls of the member 13, as will be clearly apparent by reference to Figs. 1 and 2. The refrigerant is introduced through the expansion valve into the member 13 through pipe 25 and its level is preferably maintained below the top of the member 13. The cooling medium 29, preferably liquid, within the casing 1 will tend to boil the refrigerant in the passageway or member 13, the heat being conducted through the medium of the ribs 27 and 28. As the liquid refrigerant begins to boil, it will carry off the heat from the cooling medium 29 in a well understood manner and pass off through pipe 26 to the compressor in a pressure system or back to the absorber in an absorption system. Since the level of the liquid in the member 13 is maintained below the outlet, liability of the refrigerant being drawn out of the member 13 in the liquid phase will be eliminated. Therefore the refrigerant cannot pass out of the member 13 until it has been converted into the vapor phase due to the heat exchange between the medium 29 and the refrigerant in member 13. This is important because the refrigerant must take up the maximum amount of heat before it can pass on through pipe 26. Therefore even if a compressor is used the compressor cannot exert enough "pull" to exhaust the refrigerant while in the liquid phase from the member 13.

It is important in a device of the class herein contemplated that the cooling liquid 29, whatever it may be, be maintained at a uniform temperature or at as nearly a uniform temperature as is practical throughout and it is one of the salient features of my invention that means is provided whereby the entire body or cooling liquid will be maintained at the minimum temperature and this is accomplished by the peculiar arrangement of the various elements of my invention, for example the ring shaped passageway member 13 is disposed above the receptacles 2 and 3, the bottom of the flanges 27 resting upon the receptacles 1 and 2 and the top portions of the flanges 27 preferably being spaced below the top of the receptacle 1. Therefore when the heat is absorbed from the cooling medium 29 during the vaporization of the refrigerant in the member 13, the cooling medium in the middle portion of the member 13 is colder than at any other point in the casing 1, therefore it will tend to drop to the bottom of the casing 1 as indicated by the arrows in Fig. 1 and as it passes down through the space 11 to the space 12, the warmer medium 29 will pass up through passageways 4, 5 and 6 over the top of the member 13 and come into proximity with the absorption ribs 27 so that its heat may be absorbed by the

refrigerant, thus the continued cooling of the cooling medium by the member 13 will cause a continuous circulation of the cooling medium 29 and thereby prevent stratification of the liquid in different temperatures. In this way the cooling medium 29 will be maintained at substantially the same temperature throughout so that the receptacles 2 and 3 will be capable of reducing the temperatures of their contents to a minimum and since it is possible to cause a circulation of the medium 29 it is obvious that when the system is first caused to function the temperature of the medium 29 will be reduced to a minimum more expeditiously than is possible in constructions in which there is no circulation of the cooling medium 29.

I have shown but one specific embodiment of the generic principles of my invention, it being apparent that the changes in form, proportion and minor details of construction may be resorted to without departing from the spirit of the invention or sacrificing any of its advantages.

What I claim and desire to secure by Letters-Patent is:

1. In a device of the character described, a container for cooling medium, an active refrigerant conduit mounted in the upper portion of said container, said conduit being shaped to provide a passageway through the center thereof, and a pair of cooling compartments below said conduit, said compartments being spaced to provide a cooling medium circulating passageway in alignment with said first mentioned passageway, and said compartments and said conduit being spaced a substantial distance from the walls of said container to provide a passageway therearound.

2. In a device of the character described, a container for cooling medium, a ringlike conduit for active refrigerant mounted in the upper portion of said container, said conduit having a vertical cooling medium passageway through the center thereof, and a pair of cooling compartments below said conduit, said compartments being spaced to provide a cooling medium circulating passageway in alignment with said first mentioned passageway, and said compartments and said conduit being spaced a substantial distance from the walls of said container to provide a passageway therearound.

3. In a device of the character described, a container for cooling medium, and a ring like conduit for active refrigerant mounted in the upper portion of said container and spaced a substantial distance from the top and sides thereof, said conduit having a central vertical cooling medium opening, and being provided with vertically extending fins projecting laterally therefrom into said opening and toward said side walls.

4. In a device of the character described, a container for cooling medium, a ring like conduit for active refrigerant mounted in the upper portion of said container and spaced a substantial distance from the top and sides thereof, said conduit having a central vertical cooling medium opening, and being provided with vertically extending fins projecting laterally therefrom into said opening and toward said side walls, said 5 pair of cooling compartments spaced a substantial distance from the bottom and side walls of said container below said ring like conduit and having the major portions thereof substantially vertically aligned therewith, said compartments being spaced to provide a cooling medium circulating passageway in alignment with said vertical opening.
- 10 5. In a device of the character described, a container for cooling medium, and a ring like conduit for active refrigerant mounted in the upper portion of said container, and spaced a substantial distance from the top
- 15 and sides thereof, said conduit having a central vertical cooling medium opening, and being provided with vertically extending fins projecting laterally therefrom into said opening and toward said side walls, said 20 fins being arranged to direct the cooling medium toward said central opening as the same circulates around said conduit.
- 25 6. In a device of the character described, a container for cooling medium, and a ring like conduit for active refrigerant mounted in the upper portion of said container and spaced a substantial distance from the top and sides thereof, said conduit having a central vertical cooling medium opening, and being provided with vertically extending fins projecting laterally therefrom into said 30 opening and toward said side walls, said conduit having an intake and an outlet connection extending from the top thereof through the top of said container.
- 35

In testimony whereof I affix my signature.

CHARLES W. HACK.
